CONTROL DEVICE FOR ROTARY
DUPLICATING MACHINES

Wilhelm Ritterfeld, Berlin, Germany

Application October 14, 1938, Serial No. 234,887
In Germany October 19, 1937

4 Claims. (Cl. 101—132.5)

The present invention relates to a control device for rotary duplicating machines of the type in which a copyable mirror-script original is pressed against sheets previously moistened with a readily volatilizing liquid. These known rotary duplicators consist in a printing drum with means for holding the original, a counterpressure roller, a moistener if wanted supply means for the sheet to be printed upon and—also if wanted—means to take up the sheets printed upon.

The object of the invention consists in preventing one or other part remaining switched on when the drive of the machine is switched off, as for example could be the case with the pressure roller and with the valves for the supply of liquid.

To this end, essentially the invention consists in connecting to each other two or more of the parts of the reprinting or copying machine which can be switched on and off, by means of known elements or any elements desired, for example, rods, levers, wheel, worm, friction, belt or chain gears or the like in such a way that when at least one of these elements is switched on or off, one or more of the other elements are simultaneously set in motion or stopped. As representatives of the first group of elements may be mentioned: motor, counterpressure roller, valves for delivering the liquid. Representatives of the second group: motor, counterpressure roller, valves for delivering the liquid and e. g. a device for opening the clamping device.

A further characteristic of the invention consists in that the further switching of at least one or the other elements of the mentioned first group can be proceeded with, and if desired in stages, after the other elements are already working, without further influencing other elements. The same process can be carried out when switching off but in the opposite order.

In the drawings two forms of construction made in accordance with the invention are illustrated by way of example:

Figs. 1 and 2 show the connection of the motor switch with the pressure roller respectively in elevation and in part plan, the latter to a larger scale.

Figs. 3 to 5 show details of the connection of the lever for actuating the pressure roller with the valves for the liquid.

According to Figs. 1 and 2, I provide a printing drum 1 and a pressure roller 2 which can be pressed on to the printing drum lightly or

strongly by means of an eccentric 3 in a known manner. The pressure lever 4 is used for moving the eccentric 3. The motor switch 5 has a spindle 6 on which a disc 7 is fastened, which disc has a radial slot 8 open towards the periphery. A pin 9 of the adjusting lever 10 seated on the eccentric spindle 3a engages with the slot 8. 11 indicates the various pressure positions. The securing of the lever 4 in its position at any time is effected by a spring loaded pin 12 (Fig. 10-2) which can enter into a hole at the corresponding place. If the pressure roller 2 is pressed against the printing roller 1 with the help of the lever 4, then the pin 9 rotates the disc 7, whereby the switching in of the engine 15 is affected. If the motor is switched off then the pressure roller 2 is removed from the printing roller 1. If the disc 7 is rotated suitably far then the pin 9 emerges from the slot 8. This device has the purpose of making it possible to move the pressure lever, without the engine being further affected.

In the construction according to Figs. 3-5 an eccentric disc 13 is disposed on the spindle 3a of the pressure lever 4. Against the eccentric 25 disc 13 lies a small oscillating arm 14 which is fastened to the spindle 15. The spindle 15 is under the influence of a spring 16. To the spindle 15 is fastened a valve cone 18. Besides this cone 18 the spindle also carries a gear wheel 30 17 which engages in a second gear wheel 19, on the spindle 20 of which a second valve cone 21 is disposed. This relates to a construction with two liquid supply pipes 22 and 23. Naturally one or more than two could be provided. If 35 the pressure lever 4 of the pressure roller is shifted then the eccentric disc 13 oscillates the arm 14 in such a way that the valves 18 and 21 are opened. If a stronger pressure is adjusted the part 14 slides on to the side surface of the eccentric disc 13 so that the spindle 15 and therewith also the spindle 20 are not further affected.

Having now particularly described and ascertained the nature of my said invention and in what manner the same is to be performed I declare that what I claim is:

1. A rotary duplicator for reprinting from mirror script originals on blank, previously moistened sheets comprising a printing drum, a motor for driving said printing drum, means to moisten said blank sheets, means to press the moistened sheets against the surface of said drum, means to switch on and off said motor, said moistening means and said pressing means, means for further actuating said pressing means

after switching on the motor, and means to start actuating said pressing means before said motor is switched off.

2. A rotary duplicator for reprinting from mirror script originals on blank, previously moistened sheets comprising a printing drum, a motor for driving said printing drum, means to moisten said blank sheets, means to press the moistened sheets against the surface of said drum, means to switch on and off said motor, said moistening means and said pressing means, means to further actuate in stages said pressing means after the motor is switched on and of the means to open and close the valves of said moistening device, and means to switch off in stages said pressing means before said motor and said moistening device is switched off.

3. A rotary duplicator for reprinting from mirror script originals on blank sheets comprising a printing drum, a motor to drive said printing drum, a hand lever to press said sheets against the surface of said printing drum, said

hand lever being provided with a spring actuated nose, said nose being adapted to engage in recesses of a control element, an arm connected with said hand-lever, a pin arranged on said arm and engaging a connection element arranged on the axle of said motor. 5

4. A rotary duplicator for reprinting from mirror script originals on blank previously moistened sheets comprising a printing drum, a motor to drive said drum, a hand-lever to press 10 said sheets against the surface of said printing drum, means to moisten said blank sheets, means to switch on and off said motor and said pressing means, a control element arranged on the axle of said hand-lever, said control element being 15 connected with an arm, said arm being arranged on the axle of a valve lever of said moistening device, and means to make the movement of a plurality of valve cones of said moistening device dependent on each other. 20

WILHELM RITZERFELD.
